DEHYDRATOR PLUG

Scott F. Hunt, Meriden, and Stanley W. Gilbert,
Middletown, Conn., assignors to Niles-Bement-
Pond Company, West Hartford, Conn., a cor-
poration of New Jersey

Application November 20, 1951, Serial No. 257,286

15 Claims. (Cl. 183—4.8)

1

This invention pertains to dehydrating devices for removing moisture from hermetically sealed chambers, and more particularly has reference to such devices in the form of dehydrator plugs for use in inhibiting corrosion from moisture in internal combustion engines while in storage or shipment.

Heretofore, dehydrator plugs for internal combustion engines have been made in either one of two prevailing types, viz., one in which the container for the desiccating material is permanently attached to the body of the plug during assembly of the device by the manufacturer; and the other in which the desiccant container is detachably secured to the body of the plug by means of a spring clip, wire bail, or the like.

The former type has the advantage of a permanent moisture-tight joint between the desiccant container and the body of the plug, and is thus less liable to leakage of moisture through said joint. On the other hand, this type has the disadvantage that the desiccant material can not be replaced when it is expended by absorption of moisture, and the whole plug must be discarded. The detachable type of plug has the advantage of being susceptible of disassembly in the field, to permit refilling with fresh desiccant material, thus enabling the same plug to be continued in use with new desiccant material. On the other hand, this type of plug has the disadvantage of depending upon an impositive attachment of desiccant container to the body of the plug with the attendant liability to leakage of moisture through the joint between these parts and consequent shortening of the useful life of the desiccant material. Another disadvantage of the detachable type of plugs heretofore in use is that, during disassembly for refilling with desiccant, the container must be separated from the body of the plug and inverted to fill it with desiccant material, with resulting liability of spilling the desiccant.

The primary object of this invention is to provide a dehydrator plug which has the advantages of both the permanent and detachable types of plug, without the disadvantages of either type.

Another object is to provide a dehydrator plug of the detachable type which can be readily disassembled and refilled with fresh desiccant material in the field, by use of the fingers alone, without inverting the plug during the refilling operation, and without liability to spillage of the desiccant material.

Another object is to provide a dehydrator plug 55

2

of the detachable type, wherein the desiccant container is permanently attached to the body of the plug by means of a moisture-proof sealing material which precludes any liability of moisture leakage through the joint between these parts.

With these and other objects in view which may be incident to our improvements, our invention consists of the combination and arrangement of elements hereinafter described and illustrated in the accompanying drawing, in which:

Fig. 1 is a longitudinal sectional view of a dehydrator plug constructed according to our invention, and

Fig. 2 is a top plan view of the plug shown in Fig. 1.

Referring to the drawing in detail, the reference numeral 1 indicates the body of the plug which is made of moulded, phenolic, thermo-setting, plastic material which is impervious to the penetration of moisture. Body 1 is provided with a downwardly extending, threaded plug portion 2 for screwing into a similarly threaded opening of an hermetically sealed chamber from whose interior the plug is designed to extract moisture, such as the cylinder or crank case, of an internal combustion engine. The upper part of body 1 is formed in the shape of a hollow, tubular sleeve 3, for receiving the lower end of a desiccant container comprising an open-ended glass tube 4 which holds the desiccant material 5. At the bottom of sleeve 3, the body 1 is formed with an annular shoulder 6 for the reception of an air-permeable, foraminous, sintered metal filter 7, on which the lower end of glass tube 4 seats, and which forms an air-permeable bottom for the desiccant container 4. Below shoulder 6, plug portion 2 has a central cylindrical air passage 8, extending downwardly therethrough.

Exteriorly, body 1 is provided with a plurality of flat surfaces 9, giving it a polygonal shape for engagement with a wrench to facilitate disengagement from the opening in the wall of the chamber with which the desiccator plug is used.

At diametrically opposite points, tubular extension 3 is formed with flats 10 having upwardly inclined holes 11 formed therein to receive the hooked ends 12 of a spring clip 13 which extends upwardly over the top of glass tube 4 in the form of a wire bail which engages the upper face of a plastic plug 14, as clearly shown in Figs. 1 and 2. Plug 14 is provided with an integral, upwardly flared, cylindrical stud 15 which terminates in a bead 16, adapted to engage a similar

bear 17 on the lower end of a resilient sleeve 18,

forming a part of a spark plug terminal (not shown). The sleeve 18 is shown in dotted lines in the drawing as it forms no part of this invention and is shown merely to illustrate one way in which a spark plug cable may be held in place, when our dehydrator plug is inserted in the spark plug hole of an internal combustion engine cylinder.

The horizontal, transverse portion of bail 13 is provided with a circular loop 19 which is shaped to resiliently embrace stud 15, as shown in Fig. 2, when the parts of our dehydrator plug are in assembled position as indicated in Fig. 1. The side portions of bail 13 are bent outwardly, as shown at 20 in Fig. 1, so as to fit over flats 10, and said side portions are also provided with S-shaped bends 20-a to increase the resiliency of the bail and thus facilitate its engagement over plug 14. The lower part of plug 14 is provided with an annular shoulder 21 for receiving a resilient gasket 22 which air-tightly seals the joint between the upper end of glass tube 4 and said plug, and at the same time causes plug 14 to function as a resilient abutment for bail 13. The resiliency of gasket 22 and the bent portions 20-a of bail 13 are such that said bail may be swung about its hooked ends 12 as pivots and sprung over the contoured edge of plug 14 into engagement with stud 15, as shown in Fig. 2, in which position it firmly anchors plug 14 in hermetically sealed engagement with the upper end of glass tube 4.

To disengage plug 14 from tube 4, it is only necessary to firmly press the sharply bent portions 23 of bail 19 with the thumbs, while the fingers hold the tube 4, until said bail is free from stud 15, whereupon said bail can be rotated about its pivots 12 and swung free of plug 14. The desiccant container can then be emptied and refilled through its upper end without removing tube 4 from engagement with plug body 1. A rubber gasket 24, seated in an annular recess 25 on the exterior of body 1, provides an air-tight seal between said body and a screw threaded sheet metal cup 26 which engages threads 27, on the exterior of plug portion 2, when our dehydrator plug is in storage or transit.

Desiccant material 5 may be any granular substance having a high capacity for absorbing moisture, preferably silica gel, of which at least a portion in the upper part of the container 4 has been treated with certain salts, such as an iodine or cobalt salt which, when the gel is dry, gives it a distinctive color (e. g. deep blue), that gradually changes to another distinctive color (e. g. pale pink), when saturated with moisture. A visual indication, easily observed through the transparent walls of tube 4, is thus afforded of the state of saturation of the silica gel 5, so that it can be replaced with fresh, dry gel before the original material becomes completely exhausted.

In the manufacture of our improved dehydrator plug, the filter 7 is first seated on shoulder 6 of body 1 and tube 4 is then inserted in sleeve 3 until it is in firm contact with filter 7, whereupon tube 4 is permanently cemented to sleeve 3, by means of an interposed film of a slow-setting, organic, resin cement 28, as shown in Fig. 1. While said cement is still plastic, tube 4 is filled with desiccant 5 and closed by plug 14, which is then secured in place by bail 13, as described hereinabove. The clamping action of bail 13 forces tube 4 into firm contact with filter 7, thereby insuring an air-tight closure between said tube and filter. The subsequent setting of cement 28

permanently locks tube 4 to sleeve 3 with an hermetic seal. The thickness of the cement film 28 is such as to compensate for tolerance variations in the external diameter of glass tube 4 and the internal diameter of sleeve 3, and at the same time insure a rigid, air-tight joint between these parts.

The interstices in filter 7 are such as to preclude any dust or fine particles of desiccant material from escaping from container 4 and falling into the chamber to which our dehydrator plug has been attached, after removal of transit cup 26.

By the use of an open-ended glass tube 4, which is air-tightly closed at its upper end by a detachable plug 14, and which is permanently cemented to body 1, we have provided a dehydrator device that can be readily disassembled in the field, without the use of any tools, and can be refilled with fresh desiccant material without removing and inverting the desiccant container, thereby eliminating the possibility of spilling the desiccant material during the refilling operation. This also precludes the danger of any spilled desiccant accidentally falling into the cylinder of an internal combustion engine to which the dehydrator plug is attached, which would necessitate dismantling the engine to remove said desiccant.

From the foregoing description of our invention, it is clear that we have provided a simple but novel form of dehydrating device which combines all the advantages of prior art devices of both the permanent and detachable types, without any of the disadvantages of said types of device, as set forth above.

While we have described and shown the preferred embodiment of our invention, we desire it to be understood that we do not limit ourselves to the precise details of construction and arrangement of elements disclosed by way of illustration, as these may be changed and modified by those skilled in the art without departing from the spirit of our invention or exceeding the scope of the appended claims.

We claim:

1. A dehydrating device comprising desiccant material wholly contained within an open-ended glass tube permanently attached near one end to a hollow, cylindrical body of moisture-proof, thermo-setting, plastic material, a moisture-permeable filter interposed between said end of said tube and said body and covering the entire open end area of said tube, an air-impermeable, detachable plug adapted to air-tightly close the other end of said tube, a resilient gasket interposed between said plug and tube, and resiliently yieldable means attached to said body for retaining said plug in closed position on said tube.

2. A dehydrating device according to claim 1, wherein said plug retaining means is a resilient wire bail, pivotally attached to said body, and adapted to yieldably snap over the outer end of said plug when in closed position on said tube.

3. A dehydrating device according to claim 2, wherein said plug has an outwardly extending stud which is resiliently embraced by a portion of said bail when said bail and plug are in closed position on said tube, whereby said bail is held in said closed position by said stud.

4. A dehydrating device according to claim 3, wherein said stud is provided with means for attaching a spark plug terminal to said stud.

5. A dehydrating device according to claim 1 wherein said tube is attached to said body by an interposed film of cement which forms a perma-

nent moisture-tight joint between said tube and body.

6. A dehydrating device according to claim 5, wherein the cement is a slow-setting, organic resin.

7. A dehydrating device according to claim 5, wherein at least a portion of said desiccant material changes its color upon absorption of moisture and the remainder of said material does not change its color upon absorption of moisture.

8. A dehydrator device comprising: a body member of generally tubular form having an axial opening extending therethrough, said opening having an annular shoulder intermediate its ends forming a pocket on one side of said shoulder and an inlet air passage at the other side, a desiccant container of open tubular shape having one end closed by a detachable, moisture-impermeable plug and the other end permanently engaged in said pocket above said shoulder, and a moisture permeable member extending entirely across the open end area of said tube and supported transversely in said opening and constituting a bottom support for the dessicant in said container.

9. A dehydrator device comprising: a body member of generally tubular form having an axial opening extending therethrough, said opening having an annular shoulder intermediate its ends forming a pocket on one side of said shoulder and an inlet air passage at the other side, a desiccant container of open tubular shape having one end permanently engaged in said pocket above said shoulder, and a moisture permeable member extending entirely across one end of said container and supported transversely in said opening and constituting a bottom support for the desiccant in said container, a moisture-impermeable, detachable plug for closing the other end of said container and resiliently yieldable means for retaining said plug in closed position on said container.

10. A dehydrator device according to claim 9, wherein said plug retaining means is pivotally connected to said body member and embraces the top of said plug when said plug is in engagement with said container.

11. A dehydrator device according to claim 9, wherein said desiccant container is permanently attached to said body member by an interposed film of moisture-impermeable cement.

12. A dehydrator device comprising: a body member of generally tubular form having an axial opening extending therethrough, said opening having an annular shoulder intermediate its

ends forming a pocket on one side of said shoulder and an inlet air passage at the other side, a desiccant container of open tubular shape having one end permanently engaged in said pocket, a moisture permeable member extending entirely across one end of said container and supported transversely in said opening and constituting a bottom support for desiccant in said container, a detachable plug for closing the other end of said container, a resilient gasket interposed between said plug and said container for air-tightly sealing said other end of said container, and resiliently yieldable retaining means connected to said plug and said body member to retain said plug in engagement with said container.

13. A dehydrator device according to claim 12, wherein said plug retaining means comprises a yieldable spring member having a transverse portion engaged with said plug and side leg portions pivotally connected to said body member to retain said plug in engagement with said container.

14. A dehydrator device according to claim 12, wherein said body member has an external flange and an external threaded portion at one side of said flange, a threaded sealing cup engaged with said threaded portion, and a sealing gasket disposed between said flange and said sealing cup.

15. A dehydrator device comprising: a body member of cylindrical tubular form having an axial opening extending therethrough, said opening having an annular shoulder spaced below its upper end, desiccant containing tube having a moisture-impermeable closure at one end and engaged near its other end with said body member above said shoulder, and a moisture permeable filter supported by said shoulder, engaging the abutting end of said tube, and extending across the entire open end area of said tube and also entirely across said axial opening, to constitute a bottom support for the desiccant.
